The ornamental design for a clip for an electronic device, as shown and described.

DESCRIPTION

FIG. 1 is a perspective view of a clip for an electronic device in a first configuration.

FIG. 2 is a right side view of a clip for an electronic device in a first configuration.

FIG. 3 is a left side view of a clip for an electronic device in a first configuration.

FIG. 4 is a rear view of a clip for an electronic device in a first configuration.

FIG. 5 is a front view of a clip for an electronic device in a first configuration.

FIG. 6 is a top view of a clip for an electronic device in a first configuration.

FIG. 7 is a bottom view of a clip for an electronic device in a first configuration.

FIG. 8 is a front view of a clip for an electronic device in a second configuration with the main clip portion rotated 90 degrees.

FIG. 9 is a rear view of a clip for an electronic device in a second configuration with the main clip portion rotated 90 degrees.

FIG. 10 is a left side view of a clip for an electronic device in third configuration with the upper portion tilted back 45 degrees; and,

FIG. 11 is a perspective view of a clip for an electronic device in fourth configuration with the main clip portion rotated 90 degrees and the upper portion tilted back 45 degrees.

The broken lines in the drawings depict parts of the clip for an electronic device that form no part of the claimed design.
